UNITED STATES PATENT OFFICE.

JOSEPH E. OSBORNE, OF WASHINGTON, DISTRICT OF COLUMBIA.

AWNING-FIXTURE.

1,150,296.

Specification of Letters Patent. Patented Aug. 17, 1915.

Application filed May 18, 1914. Serial No. 839,253.

To all whom it may concern:

Be it known that I, JOSEPH E. OSBORNE, a citizen of the United States, residing at Washington, in the District of Columbia, 5 have invented certain new and useful Improvements in Awning-Fixtures, of which the following is a specification.

My invention relates to awning fixtures, and particularly to such devices as are intended to be used in supporting and attaching the top rod of an awning to a building.

The invention involves, particularly a wire staple having sharpened points adapted to pass through the awning cover and 15 bend back upon the awning rod in such manner as to prevent the same from becoming accidentally disconnected from the awning rod.

The object of my invention is to provide 20 an awning fixture formed of a single wire doubled upon itself to form a loop and having sharpened points by which it may be easily and readily inserted through the cover and attached to an awning.

Furthermore, the object of my invention is to provide an awning fixture comprising 25 a single wire, doubled upon itself and having sharpened points formed integrally with the body portion thereof, and having a small bend at the angle for supporting a pulley.

Finally, the object of my invention is to provide an awning fixture, comprising a wire looped upon itself, forming a means for attaching the same to a nail or screw inserted in a window frame or other part of a 35 building, to which it is desired to attach the awning.

With the above and other objects in view, 40 my invention consists in the arrangements and details of the construction as disclosed in the accompanying drawing, forming part of this specification, and which is more particularly pointed out in the claim.

In the drawing I illustrate my invention, 45 as set forth in detail in the following description, and in which,

Figure 1 is a view in elevation, showing 50 my improved awning fixture attached to the top rod of an awning. Fig. 2 is a perspective view in elevation, showing the invention before being clamped on the awning rod. Fig. 3 is a side view, showing my improved awning fixture attached to an awning rod

and also attached to a screw inserted in the building. Fig. 4 is a rear view.

In the drawing, 1 indicates an awning, which may be of any ordinary structure and provided with a top awning rod, 2, which is usually inserted in a loop formed on the top edge of the awning material. I form my 60 awning fixture of a single piece of wire bent upon itself at 3, forming vertical side arms, 4, and sharpened extending points, 5. At the points of the angle, I form a small bend, 6, which supports the ring 7, of the pulley 8. 65 The loop formed between the vertical portions 4, forms a loop through which the screw, 9, is inserted into the frame or wall of a building, and by which the device is supported.

In the operation of my invention it is to be noted that the ring of the pulley is inserted over the points until it seats in the bend, 6. The sharpened points are then inserted through the awning covering, immediately 75 beneath the awning rod, then the said points are bent inwardly toward the vertical portion, 4, thus attaching the awning hanger to the top rod of the awning.

In my improved awning fixture I provide 80 a device which is simple in structure, inexpensive to manufacture and which may be easily and readily attached to an awning in a permanent manner, so that when the awning is removed the fixture remains secure to 85 the top rod, and when it is again desired to replace the awning the fixture need not be replaced, but inserted over the eye of the retaining screw, which is secure in the frame or wall of the building.

The mounting of the awning, as will be clearly apparent, is an operation that can be readily, quickly and easily performed. The same applies to the taking down of the awning. The removal of the awning can be 95 accomplished without separating the fixtures from the awning rod, and their application does not in any wise affect or require any change to the awning structure or the building to which the awning may be connected.

What I claim as new, and desire to secure by Letters Patent, is:

In an awning fixture comprising a single wire bent upon itself, forming vertical side arms provided with sharpened extending 105 pointed side arms having a small bend in-

termidiate their length, said bend adapted to receive the ring of a pulley, said arm portions being adapted to be inserted through an awning cover and clenched over the top 5 rod of the awning, whereby the awning may be attached to a building, substantially as described.

In testimony whereof I affix my signature in presence of two witnesses.

JOSEPH E. OSBORNE.

Witnesses:

INA E. GOLLADAY,

HARRY F. KENNEDY.
